UNITED STATES PATENT OFFICE.

ARTHUR RICHARD BALDWIN HILAWSKI, OF ZABORZE, UPPER SILESIA,
GERMANY.

COOKING-FURNACE.

SPECIFICATION forming part of Letters Patent No. 293,028, dated February 5, 1884.

Application filed November 15, 1883. (No model.) Patented in Germany November 24, 1882, No. 21,455.

To all whom it may concern:

Be it known that I, ARTHUR R. B. HILAWSKI, of Zaborze, Upper Silesia, Germany, have invented a new and Improved Coking-Furnace, of which the following is a full, clear, and exact description.

The object of my invention is to provide a new and improved furnace for converting coal into coke, in which furnace all the gases expelled from the coal are consumed and cannot escape to poison and deteriorate the surrounding air.

The invention consists in a coking-furnace constructed with a series of coking-chambers for receiving the coal to be coked, between which coking-chambers gas-chambers are arranged, into which gas is passed from the coking-chambers, the said gas-chambers being provided in their bottoms with openings leading to transverse channels connecting a series of longitudinal channels below the gas-chambers, so that the gases will circulate until exhausted, and then pass off through a suitable channel leading to the smoke-stack.

Reference is to be had to the accompanying drawings, forming a part of this specification, in which similar letters of reference indicate corresponding parts in all the figures.

Figure 1 is a cross-sectional elevation of my improved coking-furnace on the line $x-x$, Fig. 2. Fig. 2 is a sectional plan view of the same on the line $y-y$, Fig. 1. Fig. 3 is a longitudinal sectional elevation of the same on the line $x'-x'$, Fig. 1. Fig. 4 is a longitudinal sectional elevation of the same on the line $y'-y'$, Fig. 1.

The furnace A is constructed with a series of longitudinal chambers B, which have curved roofs, and are provided with one or more openings, C, in the said roofs, through which openings the coal to be converted into coke is passed into the chambers. Between each two chambers B gas-chambers D are formed, into which the gases from the coking-chambers pass, the walls of the coking-chambers being provided with slots E, inclined upward at an angle of about fourteen degrees to the bottoms of the chambers B, through which slots the gases pass from the coking-chambers into the gas-chambers. The walls of the gas-

chambers D are united at intervals by bricks D', extended across the gas-chambers. The gas-chambers are provided in their bottoms with openings F, through which the gases pass into transverse channels G, which conduct them into longitudinal channels H below the coking-chambers B. The bottoms of the coking-chambers are the roofs of the channels H, and the said bottoms are provided with a series of longitudinal slots, J. Each channel H is provided with a downwardly-extending flue, H', which leads to a transverse channel, K, connected with a smoke-stack, L. The openings F in the floors of the gas-chambers D can be closed by means of sliding blocks F', resting on the floors of the gas-chambers, which gate-blocks can be moved by means of hooks or rods introduced through openings M in the end walls of the chambers. Each channel H under the chambers B is provided at its ends with openings N, through which hooks can be introduced to remove the slags, &c., from the slots or openings J. Like openings O are provided for introducing hooks to clean the slots E. The openings N and O can be closed by means of clay blocks P. The air enters through openings R in the front and rear walls of the gas-chambers D, which openings can be closed more or less by means of suitable slides. The gases from the coal pass through the slots E into the gas-chambers D, from there through the openings F into the channels G and H, and from these channels up through the openings J, through the coal again, and so on, and only the worthless gases—that is, the non-combustible gases—pass off through the channel K and the smoke-stack L. All the heat in the gases is utilized and none is lost. The chambers are heated to such an extent that if the coke is removed and fresh coals are placed into the chambers the gases will be driven out immediately, and the process of coking begins as soon as the coals are placed in the furnace. The coke produced is very homogeneous, very compact, and not porous. The entire furnace is very simple in construction.

Having thus fully described my invention, I claim as new and desire to secure by Letters Patent—

A coking-furnace constructed with a series of coking-chambers, B, gas-chambers D between them, longitudinal channels H below the coking-chambers, transverse channels G, 5 connecting the channels H, and a channel, K, communicating with the channels H by the flues H', and leading to the smoke-stack, and slots J, communicating with the channels H

and the coking-chamber B, substantially as herein shown and described, and for the purpose set forth. 10

ARTHUR RICHARD BALDWIN HILTAWSKI.
